UNITED STATES PATENT OFFICE.

JOSEPH W. C. MEIKLE, OF BALTIMORE, MARYLAND, ASSIGNOR OF ONE-HALF TO WILLIAM JEROME SOPER, OF BALTIMORE, MARYLAND; HELEN HOLSTON MEIKLE, EXECUTRIX OF SAID JOSEPH W. C. MEIKLE, DECEASED, ASSIGNOR OF ONE-FOURTH TO WILLIAM JEROME SOPER, OF BALTIMORE, MARYLAND.

PAPER BAG.

Application filed March 8, 1927. Serial No. 173,625.

This invention relates to improvements in paper bags and has particular reference to a bag embodying a novel construction of flap to close the open end with openings therethrough by which the same may be suspended or carried.

One object of my invention is to provide a bag which may be used for various purposes, but which is especially designed for the use of bakers who deliver their products, such as bread, rolls, buns etc. directly to the consumer's home in the early morning hours and while the servants or members of a household are still asleep.

15 Early morning delivery has become a common practice with bakers but difficulties are experienced, and some objections to such delivery are made, because of the lack of protection for the breads or other products, 20 at the homes of the consumers at a time when there is no one about to receive the products.

Often, the bread, in a bag or waxed paper, is merely laid in the doorway of the consumer and is exposed to the weather, 25 ants or bugs and sometimes to stay animals or rats, and these objectionable conditions materially interfere with the expansion of the baker's business in so far as direct early 30 morning delivery to the consumer is concerned.

My invention therefore has for its object to provide a bag in which the baker's products may be placed, which will effectively 35 protect the contents, which will be sufficiently strong to sustain the weight of the contents when hung from one end; which will have a novel form of flap and openings by 40 which the bag may be hung on a door-knob or other suspension means and which, when so hung, will keep the flap of the bag closed and prevent the entrance of dust, dirt or water, if the bag happens to be exposed to rain or snow.

45 With these objects in view, the invention is illustrated in the accompanying drawing, wherein,

Fig. 1 illustrates the flap or collapsed bag with its flap up-turned.

50 Fig. 2 shows a vertical sectional detail through the flap collapsed bag with the flap turned up,—the section being taken on the line 2—2 of Fig. 1.

Fig. 3 illustrates an enlarged cross-sectional detail through the bag with the flap turned down showing the same as it would appear on the line 3—3 of Fig. 1.

Fig. 4 shows a vertical sectional detail through the same with the flap turned down.

Fig. 5 shows the improved bag with its contents hung from the knob of a door, and

Fig. 6 shows the detached reinforcing strip and flap-member.

Referring to the drawings, the numeral 10, designates the body of the paper bag; 11, the bottom thereof and 12 the longitudinal seam.

In so far as my invention is concerned, it is immaterial as to just what form of bottom the bag may have or where the longitudinal seam 12 is located, but it is important that the bag be provided with a flap at its open end in order to effectually close the latter and protect the contents.

It is also desirable that the bag be reinforced at its mouth or open end because I desire to suspend the bag and its contents from that end.

In carrying out my invention, I preferably provide a reinforcement that not only reinforces both walls of the bag, but which also produces the flap by which the bag may be closed.

For the purpose of distinguishing the walls of the bag, I designate the front wall 14 and the rear wall 15, and the seam 12 extends, in this instance, lengthwise of the rear wall.

The upper edges 16 and 17 of the front and rear walls, in the present disclosure, are shown as being in alignment in a crosswise direction between the opposite side edges 18 of the bag.

In further carrying out my invention, I provide a reinforcing member 19 of a peculiar shape as illustrated in Fig. 6 of the drawing.

This reinforcing member has a lower body-portion 20, that is wider than an upper flap-portion 21 thereof, and in practice, said lower wider portion is preferably, at least twice the width of the said narrower flap portion.

The upper narrower flap portion 21, in the form shown, has a height about equal to the height of the lower portion so that

the reinforcing member is about twice as high at the flap portion as through the lower portion. It is not essential however that these proportions be maintained.

5 In the present disclosure of reinforcement, the upper flap-portion 21 is located at one side and at the upper edge of the entire reinforcing member, while the lower body-portion has an extension 22 projecting laterally 10 from the base of the flap-portion.

When this reinforcing member is applied to the open end of the bag the extension 22, will be cemented or glued to the rear wall 15, of the bag and extend crosswise thereof 15 from side to side and with its upper edge 23 flush with the upper edge 17 of said rear wall, as shown in Fig. 2 of the drawing.

Of course, this extension 22, will have its entire contacting surface with wall 15, glued 20 to the latter.

In the form shown, one end edge 24, of this extension around one side edge 18 of the bag-body and is glued against the front wall 14, as shown in Fig. 3 of the drawing.

25 After the extension 22 is glued to the bag-wall 15, it will then be folded on the line 25 and passed around the opposite side edge 18 of the bag to the front and the lower portion 20, beneath the flap 21, will then be

30 glued to the front wall 14 and will extend across the latter from side to side until its edge 26, overlaps the edge 24 of the lateral extension as can be seen in Fig. 3 of the drawing.

35 It will thus be seen that the reinforcing member is glued or otherwise attached to both the rear and front walls of the bag around the open end but that the flap-portion 21 will extend beyond the end edges 40 16-17 of said open end.

The flap 21 will then be turned down on the fold line 27 and laid against the reinforcing extension 22 at the rear side of the bag so that a single punch may be passed 45 through the flap, the reinforcement and the bag-walls, and thus produce registering perforations 28 and 29 in the opposed rear and front walls and a like perforation 30 in the flap 21.

50 Of course, the perforation 28, extends through the reinforcement extension 22 and the rear wall 15 of the bag, while the perforation 29, extends also through the reinforcement and the front wall 14 of the bag

55 so that each of those perforations passes through at least two thicknesses of material

and the walls of the perforations are thereby strengthened.

I prefer to make the perforations of a circular shape and of a size to enable them 60 to readily receive the knob of a door on which the bag may be hung as herein before set forth.

In Fig. 5, I show a doorway; a door 31 and a knob 32 on the door, and the bag containing, say two loaves of bread 33, is hung on the door-knob 32 with the flap 21 turned down and the bag thus closed.

Of course, the bag may be hung on any projection other than a door-knob that may 70 be passed through the registering perforations.

Having described my invention, I claim,—

1. A bag having front and rear walls and 75 open at one end said bag having a reinforcement attached thereto adjacent to said open end said reinforcement extending across the front and rear walls and at the front wall the reinforcement being deeper and projecting beyond the open end of the bag and 80 forming a flap for said open end, and said reinforcement, front and rear walls and the flap of the reinforcement each having an opening therein, all of which openings will 85 register when the flap is turned down.

2. A bag having front and rear walls and open at one end, a reinforcing strip attached to and extending crosswise of the rear wall and also extending around and across the front wall at the open end of the bag,—said 90 reinforcing strip carrying an extension at its upper side which forms a flap for the open end of the bag and said front and rear reinforcement portions and the flap thereof each having an opening therethrough all of 95 which openings will register when the flap is turned down.

3. A bag having a front wall and a rear wall and open at one end and also having a reinforcement strip extending all the way 100 across the open end from one side edge of the bag to the other side edge thereof,—said reinforcement strip being attached to the bag-wall and alone forming a complete flap to cover the entire end-opening and folding 105 over against the other bag-wall the said reinforcement flap and both bag-walls each having an opening which openings will register when the reinforcement covering flap is turned down.

In testimony whereof I affix my signature.
JOSEPH W. C. MEIKLE.
